[57] CLAIM

The ornamental design for a combined club bag and sport bag, as shown and described.

DESCRIPTION

FIG. 1 is a front elevational view of a combined club bag and sport bag showing my new design;

FIG. 2 is a rear elevational view thereof;

FIG. 3 is a right side elevational view thereof, the opposite side being a mirror image thereof;

FIG. 4 is a top plan view thereof;

FIG. 5 is a bottom plan view thereof;

FIG. 6 is a side elevational view of the other side of the sport bag portion shown in FIG. 1 of the combined club bag and sport bag when that sport bag portion is separated from the combination shown in FIGS. 1-5; FIG. 6 is also a side elevational view of this other side of the club bag portion shown in FIG. 2 of the combined club bag and sport bag when that club bag portion is separated from the combination shown in FIGS. 1-5, the shoulder strap being omitted;

FIG. 7 is an end view of one end of the sport bag portion shown in FIGS. 1 and 6, the other end being a mirror image thereof;

FIG. 8 is a top plan view of the sport bag portion shown in FIGS. 1, 6 and 7;

FIG. 9 is a bottom plan view of the sport bag portion shown in FIGS. 1, 6 7 and 8;

FIG. 10 is an end view of one end of the club bag portion shown in FIGS. 2 and 6 and with the shoulder strap removed, the other end being a mirror image thereof;

FIG. 11 is a top plan view of the club bag portion shown in FIGS. 2, 6, and 10 and with the shoulder strap removed; and

FIG. 12 is a bottom plan view of the club bag portion shown in FIGS. 2, 6, 10 and 11 with the shoulder strap removed.
